UNITED STATES PATENT OFFICE.

ELBRIDGE S. FELTCH AND CHARLES E. STONE, OF AMESBURY, MASSACHUSETTS.

MACHINE FOR DRILLING TIRES AND FELLIES OF WHEELS.

SPECIFICATION forming part of Letters Patent No. 576,305, dated February 2, 1897.

Application filed January 28, 1896. Serial No. 577,109. (No model.)

To all whom it may concern.

Be it known that we, ELBRIDGE S. FELTCH and CHARLES E. STONE, citizens of the United States, and residents of Amesbury, in the county of Essex and State of Massachusetts, have invented certain new and useful Improvements in Machines for Drilling the Tires and Fellies of Wheels, of which the following is a specification, reference being had to the accompanying drawings, forming a part thereof, in which similar letters of reference indicate corresponding parts.

This invention relates to drilling-machines, and particularly to that class thereof which are designed for use in boring the tires and fellies of wheels and countersinking the bores in the tire; and the object thereof is to provide a machine of this class which is so constructed and arranged that the wheel after having been placed upon the machine is retained thereon until the entire operation is completed, said wheel being revolubly supported and being turned on its support until the entire tire and the fellies are suitably bored; and with this and other objects in view the invention consists in the construction, combination, and arrangement of parts hereinafter described and claimed.

It is necessary to employ different drills in boring the tires, the fellies, and countersinking the bores in the tires of wheels, and at least three different drills are required, and in most machines of this class it is necessary to take the wheel from the machine while changing the drills, but in our improvement this difficulty is avoided, and we employ a revoluble tripod, which may be provided with any desired number of drill-heads, and these different drill-heads are adapted to carry the different drills required.

The invention is fully disclosed in the following specification, of which the accompanying drawings form a part, in which—

Figure 1 is a side elevation of our improved drilling-machine; Fig. 2, a plan view thereof; Fig. 3, a side elevation of one form of tripod which we employ, showing one drill-head connected therewith; Fig. 4, an end view thereof, showing three drill-heads; Fig. 5, a section on the line 5 5, looking in the direction of the arrow α ; Fig. 6, an end view of a plate pro-

vided with a central tubular extension by means of which the tripod and the tripod-spindle are connected with the frame of the machine. Fig. 7 is a plan view of a modified form of turret, showing two drill-heads connected therewith; Fig. 8, a section on the line 8 8 of Fig. 7, and Fig. 9 is a side elevation of a sleeve which forms a detail of the construction shown in Fig. 7.

In the practice of our invention we employ a frame comprising end standards A and A^2 , which are united at the top by horizontal side bars A^3 and A^4 , and the horizontal side bars A^3 and A^4 are firmly connected by cross-bars or plates a , a^2 , and a^3 , and this frame is composed, preferably, of wood, and is also made strong and substantial, but the exact form thereof is immaterial, as is also the method of its construction.

Passing centrally and longitudinally through the lower portion of the frame is a shaft B, which is provided with three pulley-wheels B^2 , B^3 , and B^4 , which are of different sizes and increase in size in the order named, and on the outer end of said shaft is a power-wheel B^5 , to which in practice a power-belt is applied.

Secured to the cross pieces or bars a and a^2 in the top of the frame, and on the upper sides thereof, are housings C and C^2 , through which the driving shaft or spindle D passes, and mounted on said driving shaft or spindle D are pulley-wheels D^2 , D^3 , and D^4 , which decrease in size in the order named, and said pulley-wheels are designed to be operated by belts E and E^2 , which are mounted on the wheels D^3 and D^4 and also on the wheels B^3 and B^4 on the shaft B, and it will be understood that either one of these belts may serve to operate the driving shaft or spindle D, and that two or three thereof may be employed, if required.

The driving shaft or spindle D is movably mounted in the housings C and C^2 , and is adapted to be moved longitudinally therein, and in this operation it passes through said housings in the usual manner, and the pulley-wheels D^2 , D^3 , and D^4 are also connected therewith as usual in this class of devices, and these elements of construction are all substantially the same as those heretofore employed in this class of machines and form no part of our

present invention. In order to operate this shaft, we connect with the outer end thereof a lever F, and this lever is connected with the shaft by a collar F² in the usual manner, said 5 collar being held in place by rings or bands F³, one of which is mounted at each side thereof, and said lever is connected at one end with the frame, as shown at F⁴, and the handle thereof extends across the bar F⁵, which is 10 also connected with the frame and on which the handle end of said lever is free to slide.

The inner end of the driving shaft or spindle D is provided with a head d, in the outer end of which is formed a central cavity or recess 15 d², (shown in dotted lines in Figs. 3 and 7,) and which is adapted to receive the end of a drill-spindle, and at each side thereof is formed a cavity or recess d³, also shown in dotted lines in said figures, which are adapted to receive 20 pins or projections secured to the drill-spindle, which is mounted in the drill-heads, as hereinafter described.

We also employ a turret, which consists of a head G, which is shown in Figs. 3, 4, and 5, 25 and which, as shown in the drawings, is provided with a number of drill-heads G², but one of which is shown in Fig. 3 and three of which are shown in Fig. 4, and this turret is adapted to be connected with a turret-spindle g by 30 means of a rivet g², as shown in Fig. 3, and said turret-spindle is passed through a sleeve g³, which is formed on a plate g⁴, which is bolted to the cross-bar a² of the frame, as shown in Fig. 1, and the end of the turret-spindle g extends through said cross-bar a² 35 of the frame and is provided with a circular head, ring, or band g⁵, between which and the plate g⁴ or cross-bar a² is mounted a strong spiral spring g⁶, and secured in the outer end 40 of the sleeve g³ is a pin g⁷, (shown in dotted lines in Fig. 3,) which is adapted to project into a cavity or recess g⁸, formed in the adjacent end of the head G, and also shown in dotted lines in said figure.

45 Each of the drill-heads G² consists of a band H, through which passes a drill-spindle h, (shown in dotted lines in Figs. 3 and 7,) the outer end of which is provided with a head h², which is provided centrally with a hole or 50 opening h³, into which the drill or tool is adapted to be inserted and wherein it may be fastened by means of a set-screw h⁴, and the inner end of the spindle h is provided with a collar or band h⁵, which is secured thereto in 55 any desired manner and which is provided with pins or projections h⁶, which are adapted to enter the holes or openings d³ in the head d of the driving shaft or spindle D, and formed on the end of the drill h is a conical projection h⁷, which is adapted to enter the conical cavity or recess d², which is also formed in the head d of the drive shaft or spindle D. It will be understood that by means of this 60 construction the drill-spindle h is free to revolve in the tubular head or sleeve H and that any number of these tubular heads or sleeves may be employed, three thereof being

shown in Fig. 4, and in Fig. 2 we have shown an ordinary drilling-tool H² connected with one of these drill-spindles and a reaming-tool H³ connected with another. 70

We also provide a wheel-cup K, which is mounted at the forward end of the frame of the machine and is capable of vertical adjustment by means of a screw or screws K², (shown 75 in Fig. 1,) and this wheel-cup is also capable of longitudinal adjustment on the supports thereof, which are shown in dotted lines at K³ in said figure, and secured to the upper portion of the frame of the machine and to the side bars A³ and A⁴ thereof are vertically-adjustable spring-supports k, which are adapted to support the tire of a wheel and which are vertically adjustable by means of screws k², one of which is shown in Fig. 1, and secured longitudinally and centrally of the frame between said supports is a sliding plate L, the end of which is provided with a metal block L², which is connected therewith by means of a tongue-and-groove or dovetailed 80 coupling, as shown at L³, and the outer surface of this block is slightly curved or segmental in form, so as to correspond with the form of a felly of a wheel, and these blocks L² are preferably just the length of the felly- 85 plates between the holes, and by placing the joint of the felly at one end of a block and drilling one hole and then placing the joint at the other end of the block and drilling the other hole these holes will come exactly right 90 for the felly-plates and without marking the same. 95

Secured to the side bar A³ of the frame and to the upper surface thereof is a plate-spring M, which is adapted to project over the tire 100 and felly of a wheel when the latter is in position, as shown in Fig. 2, and pivotally connected with said spring is a rod m, the lower end of which is connected with a foot-pedal m², as shown in Fig. 1, and the operation of this form of construction will be readily understood from the foregoing description, when taken in connection with the accompanying drawings and the following statement thereof. 105

110 It will be understood that the turret-spindle g is adapted to slide in the plate g⁴ and the sleeve g³, which is formed thereon, and the turret-head G is rigidly connected with the outer end of the turret-spindle, and in 115 order to drill the holes for the tire-bolts the hub of the wheel is placed in the wheel-cup, as shown in Fig. 2, and the tire and felly on the bearings or supports k, and the spring M is then forced down by means of the pedal m² onto the tire, and by this operation the wheel is firmly held in position. In order to 120 drill a tire, the turret-head G is turned until the drill-head H, provided with the required 125 drill or tool, is opposite the driving-spindle D. The said driving-spindle is then brought forward by means of the lever F, in which 130 operation it connects with the drill-spindle h, as hereinbefore described, and in order to

countersink the drill-holes in the tire to provide room for the heads of the bolts the driving-spindle is moved backward and the turret-head turned so as to bring the drill head or 5 spindle provided with the reaming-drill into line with said driving-spindle, and the operation above described is repeated, and after the bore in the tire has been countersunk the turret-head is again turned so as to bring the 10 spindle provided with the drill which is designed for use in boring fellies into line with the driving-spindle.

It will thus be seen that the tire may be bored and the bores thereof countersunk and 15 the fellies bored without moving the wheel from the machine, all that is necessary being to revolve the turret-head so as to bring the 20 driving-spindle provided with the necessary tools into line with the driving-spindle D, and all that is necessary in order to bore the tire and the fellies and to countersink the bores of the 25 tire, as above described, throughout the entire circumference of the wheel is to simply revolve the wheel in the wheel-cup and to operate the turret-head and the driving-spindle as above described, and this operation can 30 be performed as rapidly and expeditiously as desired. When the lever F is operated in this manner, the driving-spindle slides 35 through the pulleys D², D³, and D⁴, and the housings C and C² and the clutching device on the end of the driving-spindle, which consists of the head d, provided with the holes or openings d² and d³, engage with the corresponding devices on the end of the drill-spindle h, as hereinafter described, and said drill-spindle turns easily with the sleeve or head H. The different sizes of drills are held in 40 the drill-spindle h by the set-screw h⁴, and the turret-head is drawn back each time that the driving-spindle D is moved backward by the spring g⁶, thereby drawing the drills out of the wheel or the tire and fellies thereof, and in the process of drilling, as hereinbefore 45 described, the driving-spindle D forces the turret-head G away from the plate g⁴ and the sleeve g⁸, connected therewith, by drawing the turret-spindle g therethrough and by compressing the spring g⁶ between the cross-bar a² and the plate g⁴. After releasing the 50 lever F the spring g⁶ draws the turret-head G back to its place, or to the position shown in Fig. 3, and the driving-spindle goes back far enough to allow the turret-head to be involved in such manner that the drill-heads H will not strike the end of the driving-spindle. 55

The turret-head G is held in each respective position by means of the pin or pins g⁷, connected with the end of the sleeve g⁸ and 60 operating in connection with the corresponding hole or holes g⁹, formed in the turret-head, and in order to avoid confusion we have only shown one of the drill-heads in Fig. 3; but it will be understood that any desired number 65 thereof may be employed, and the inner end of the turret-spindle g projects within the rim of the pulley d², which is mounted on the

driving-spindle so as to employ as little space as possible, and by means of the vertical and longitudinal adjustment of the wheel-cup we 70 provide for drilling wheels of different diameters and provided with tires and fellies of different widths or thicknesses.

In Figs. 7, 8, and 9 we have shown a modification of the turret-head shown in Fig. 3, and hereinbefore described, and this form of construction may be adapted instead of that shown in Fig. 3, if preferred. In this construction each of the drill-heads is capable of longitudinal movement independent of the 80 other and slides on or in the head G. In this form of construction we provide a tubular head G, which is provided with a central bore drilled to within about one-half inch of the outer end thereof, and the outer surface of the 85 tubular head G is provided with a plurality of dovetailed grooves N, four of which are shown in Fig. 8, and the drill heads or sleeves H are provided with shanks n, to which are secured or on which are formed arms n², 90 which are adapted to slide in said dovetailed grooves, and passing through the inner end of each of said arms is a set-screw O, the inner end of which passes through a slot O², formed in the bottom of the dovetailed grooves, and 95 the inner end of the set-screw O is reduced in size and adapted to enter an annular groove O³, formed in the spindle g. The spindle g may be connected with the frame of the machine in any desired manner, and that portion of the end thereof within the turret-head G is reduced in size, and mounted thereon is a spiral spring g⁶, and mounted on the inner end of the reduced portion of the spindle g is a tubular sleeve P, the outer end 100 of which is provided with a flange P², on which is formed one or more projections or shoulders P³.

It will be understood that any desired number of the drill-heads H may be employed, 110 and that each turret-head G may be provided with any desired number of the dovetailed grooves N, and that a corresponding number of the drill-heads H may be employed, and that each of said drill-heads is provided with 115 an arm n² and a set-screw O, and that each of the dovetailed grooves N is provided with a slot O², which communicates with the central bore of the turret-head, and the shoulders or projections P³ are adapted to operate in connection with the inner ends of the set-screw O, which project through the space between the turret-head and the reduced end of the spindle g and into the annular groove O³, formed therein. Said spindle g is also provided at one side thereof with a longitudinal groove or recess R, in which the inner end of the set-screw O is adapted to slide; and in the operation of this form of construction when the drive-spindle D is operated and brought 120 in contact with one of the drill-heads the arm a², connected therewith, is forced outwardly, and in this operation the inner end of the set-screw O, connected therewith, slides 125

in the groove R in the spindle g, and said set-screw compresses the spring g⁶ by forcing outwardly the sleeve P, and each of the other 5
5 end of the set-screw O, connected therewith, which remains in the annular groove O³, and whenever the drive spindle or shaft D is moved backwardly the spring g⁶ will at once 10
10 return the drill-head, which has been forced outwardly, to its normal position, in which position the inner end of the set-screw O, connected therewith, will project through the annular groove O³ in the spindle g, and the tripod-head 15
15 may be again revolved, so as to bring another drill-head in line with the driving-spindle. It will thus be seen that this form of construction is substantially the same in the results produced as that hereinbefore described, the 20
20 principal difference being that in this form each of the drill-heads moves independently of the other or slides independently thereof.

It is evident that other changes in and modifications of the construction herein described 25
25 may be made without departing from the spirit of our invention or sacrificing its advantages; and we reserve the right to make all such changes in and modifications of the construction as fairly come within the scope of the invention; and though we have described 30
30 our improvement as a machine for drilling wheel-tires, &c., it is evident that the same may be employed for drilling many other articles and as a drilling-machine for general purposes.

35 We also employ an idler by means of which two different speeds may be obtained without stopping the machine, and this device is operated so as to loosen one of the belts E or E² and tighten the other, and it is connected 40
40 with the side of the frame and consists of the parts S, S², S³, and S⁴, which are connected by means of set-screws, but these devices form no part of this invention and the construction and operation thereof are not there- 45
45 fore described in detail.

Having fully described our invention, we claim as new and desire to secure by Letters Patent—

1. In a machine for drilling the tires and

fellies of a wheel, the combination of a driving spindle or shaft, a revoluble turret mounted in front thereof, and provided with drill-heads which are adapted to be brought in line therewith, said machine being also provided with a wheel-cup which is adapted to receive the hub of a wheel and to support the wheel in horizontal position in such manner, that the tire thereof, will be in line with the driving or drill shaft, and said frame being also provided with an adjustable plate provided with a block or head which is adapted to press upon the inner side of the felly of the wheel, and said frame being also provided at each side of said adjustable plate with vertically-adjustable supports for the tire of the wheel, and with a plate-spring which is adapted to press upon the upper side of the tire, and a rod pivotally connected therewith and with a foot-pedal, substantially as shown and described. 70

2. In a tire-drilling machine, the combination of a longitudinally-movable driving spindle or shaft, and means for operating the same, of a plurality of drilling-heads each of which is connected with a central head which is revolubly mounted on a spindle, and each of which is provided with a drilling-spindle, with which a drill or other tool may be connected, and each of said drilling-heads being also adapted to be brought in line with the driving spindle or shaft, and said central head with which the drilling-heads are connected, being also longitudinally movable, and the spindle by which it is supported being passed through a plate provided with a sleeve or tubular extension, and which is connected with the frame of the machine, substantially as shown and described. 75
80
85

In testimony that we claim the foregoing as our invention we have signed our names, in presence of the subscribing witnesses, this 18th day of January, 1896.

ELBRIDGE S. FELTCH.
CHARLES E. STONE.
